MAGAZINE TOOL

Howard T. Hallowell, Jenkintown, and Joseph P. Villo, Glenside, Pa., assignors to Standard Pressed Steel Co., Jenkintown, Pa., a corporation of Pennsylvania

Application March 6, 1946, Serial No. 652,284

10 Claims. (Cl. 279—75)

1

This invention relates to magazine tools and a primary object of the invention is to provide a generally improved tool of this class, as herein-after more specifically set forth.

A more specific object is to provide a tool of the stated class having improved means for holding the several component tool elements for presentation to the work, and for retaining the said elements releasably in the holder.

Still more specifically the invention contemplates the provision of improved chuck means affording releasable but positive means for retaining the said tool elements, said chucks being characterized also by simplicity of form and economy of manufacture.

The invention further resides in certain structural details hereinafter described and illustrated in the attached drawings wherein:

Fig. 1 is a side view of a tool made in accordance with the invention;

Fig. 2 is a sectional view on the line 2—2, Fig. 1;

Fig. 3 is a sectional view on the line 3—3, Fig. 2;

Fig. 4 is a sectional view on the line 4—4, Fig. 1;

Fig. 5 is a view in perspective of one of the component tool elements;

Fig. 6 is a view in perspective of another form of tool element which may be included in the kit;

Fig. 7 is a fragmentary sectional view illustrating still another form of tool element;

Fig. 8 is an enlarged sectional view on the line 8—8, Fig. 1;

Fig. 9 is a sectional view on the line 9—9, Fig. 8;

Fig. 10 is a sectional view corresponding to Fig. 8 showing the chuck elements in release positions;

Fig. 11 is a fragmentary side view of a magazine tool showing a modified form of chuck;

Fig. 12 is an enlarged sectional view on the line 12—12, Fig. 11;

Fig. 13 is a fragmentary side view of a magazine tool showing a still further modification;

Fig. 14 is an enlarged sectional view on the line 14—14, Fig. 13;

Fig. 15 is a sectional view corresponding to Fig. 14 showing the elements of the chuck device in release positions;

Fig. 16 is an enlarged sectional view on the line 15—15, Fig. 13;

Fig. 17 is a view corresponding to Fig. 13 but illustrating a further modification of the invention;

Fig. 18 is a sectional view on the line 18—18, Fig. 17, and

2

Fig. 19 is a view corresponding to Fig. 18 but showing the elements of the chuck in the tool retaining positions.

With reference to Figs. 1, 2, and 3 of the drawings, the tool comprises a body portion 1 in the form in the present instance of an elongated handle which is hollow so as to provide in the interior thereof a chamber 2 for reception of various tool elements of a character hereinafter described. The body portion 1 is provided with a screw cap 3 which acts to close the chamber 2 and which may be readily removed to afford access to the chamber. At the opposite end of the body 1 is a tip element 4, preferably of metal, 15 said tip comprising a pair of laterally spaced terminal bosses or ears 5—5. Between these ears is supported a stem 6, said stem having a circular disc-like end portion 7 which is confined closely between the ears and through which extends a rivet 8 which forms a pivot about which the stem 6 may be angularly adjusted with respect to the body portion 1. The peripheral edge of the terminal portion 7 is provided with a plurality of notches or recesses 9 which are adapted to receive a spring-pressed detent 10 in the wall of the tip 4 between the ears 5—5, see Fig. 3, said detent acting to releasably anchor the stem 6 in various different angular positions with respect to the body 1. These several positions are indicated in broken lines in Fig. 1, the stem 6 being shown in full lines in an adjusted position aligned with the longitudinal axis of the elongated body member 1.

The stem 6 terminates at its outer end in an hexagonal portion 11 and from this outer end the stem is recessed axially with an hexagonal recess adapted to receive the correspondingly formed butt end 12 of a tool element 13 of the character for example shown in Fig. 5. The element 13 has an hexagonal outer end portion 14 of predetermined dimensions adapted for insertion in the hexagonal socket of a socketed screw of given size. Similar tool elements wherein hexagonal end portions 14 are of different sizes may be included in the assembly and, when not in use, may be stored within the chamber 2 in the body portion 1. It will be noted that the element 13 has in each corner of the hexagonal butt portion 12 a notch 15, said notches being equidistant from the butt extremity of the element and having a function hereinafter described.

It will be apparent that the stem 6 may be adjusted angularly with respect to the handle portion 1 to a position which is best calculated to facilitate insertion of the wrench in the screw

socket and subsequent manipulation of the wrench to drive or release the screw. When in the position shown in full lines in Fig. 1 and in Fig. 2, the device may be used as a conventional screw driver; whereas when the handle 1 is adjusted to the position shown in broken lines in Fig. 1, the wrench may be used as an angle wrench with a materially increased leverage resulting from the radial position of the handle with respect to the turning axis of the screw and of the wrench element.

It has been found desirable, in order to prevent the tool from buckling at the pivot joint 8 under misapplied pressure while in use in the straight line position, to provide a positive locking means for this adjustment. This locking means, as shown in Fig. 4, consists of a pin latch 16 in the side of the part 7 which is urged outwardly by a spring 17. When the stem 6 is in the straight line position with respect to the handle, as shown in Fig. 1 (full line) and Fig. 2, the latch 16 will register with a socket opening 18 in the confronting ear 5 and will be forced into said socket by the spring 17. The stem will then be positively locked in the aforesaid position. In any other position of the stem, the latch 16 will be held in retracted position by contact of the outer end thereof with the inner face of said ear.

The latch may be released from the socket 18, so as to permit adjustment of the stem 6, through the medium of a button 19 which occupies the outer end of the socket opening and projects beyond the outer face of the said ear. The inner end of the button is enlarged so as to provide a shoulder 21, and the metal of the ear 5 at the outer end of the socket 18 is upset as indicated at 20 so as to form an abutment for the shoulder which retains the button in the socket against the pressure of the spring 17 applied through the latch 16. By pressing the button inwardly the latch may be forced inwardly to an extent clearing the socket 18 and releasing the stem for adjustment. As illustrated, the abutting ends of the latch pin 16 and button 19 are convexed or beveled at the edge so as to facilitate positioning of the end surfaces at the parting line between the stem and the surface of the ear 5 when the stem is to be adjusted.

Reference has been made above to the notches 15 in the butt end of the tool element 13. These notches are arranged so that when the tool element is normally seated in the socket of the stem 6, as illustrated in Fig. 8 wherein the inner end of the tool element engages a shoulder 22 at the inner end of the socket, the said notches will lie in a plane normal to the axis of the stem which intersects an aperture 23 in the wall of the stem. Occupying this aperture is an element 24 which is spherical in the present instance, and the inner end of the aperture 23 is of a reduced diameter precluding passage of the element 24 into the tool socket of the stem while permitting a portion of the element 24 to project into said socket. When the tool element 13 is in the aforesaid normal position in the socket, the element 24, if projecting beyond the inner end of the aperture 23, will enter that one of the notches 15 which at the moment registers with the aperture. It will be noted that the aperture 23 is located at the juncture of two of the sides of the polygonal tool-receiving socket of the stem 6 and that in any position which the tool element 13 may occupy in the stem socket, one of the notches 15 will register with the aperture 23 as described.

Mounted on the outer cylindrical surface of

the stem 6 is a sleeve 25 which forms with the surface of the stem a chamber 26 in which the element 24 is housed. The sleeve is adjustable on and longitudinally of the stem 6 and the wall 27 of the chamber 26 is inclined to the longitudinal axis of the stem and is arranged so that when the sleeve is moved in one direction, in the present instance toward the outer end of the stem, the wall 27 will engage the element 24 and by camming action will tend to force the element 24 inwardly of the aperture 23 and into the registering notch 15 of the tool element 13. In this manner the element 24 will be positively retained in a position locking the tool element 13 in the stem.

When the sleeve 25 is moved in the opposite direction on the stem, the element 24 is released and is permitted by reason of the increased diameter of the chamber 26 to move outwardly in the aperture 23 to an extent clearing the inner restricted end thereof as shown in Fig. 10, whereupon the tool element 13 is freed for withdrawal from the stem socket.

The sleeve 25 further comprises a recess 28 in the inner surface and at one end thereof, and in this recess, which in the present instance extends completely around the inner periphery of the sleeve, is mounted a split ring 29 of spring steel which is stressed so as to exert pressure against the outer surface of the stem 6 as illustrated in Fig. 9. Thereby the element 29 creates friction between the sleeve and the stem which tends to retain the sleeve in adjusted position on the stem.

A modification of this tool element retaining device is illustrated in Figs. 11 and 12 wherein the stem 6a of the tool, which contains the polygonal tool element socket as described above, is threaded at 31 and is provided with a sleeve 32 having internal threads at one end as indicated at 33 for operative engagement with the threads 31. This sleeve is provided with the typical inclined surface 34 at the inside thereof which functions as a cam to force a spherical element 24a into the inner end of its retaining aperture 23a and into the notch 15a of a tool element 13a which corresponds to the element 13 described above. By rotating the sleeve 32 it may be caused to move longitudinally of the stem to engage or release the element 24a as may be desired. The use of the threads 31-33 insures a proper retention of the sleeve in the longitudinally adjusted position and in this case a frictioning device such as described in the previous embodiment is not required.

Still another device for retaining the tool elements of the character of 13 previously described is illustrated in Figs. 13 to 16 inclusive. In this case the retaining element 24b is controlled by a sleeve 35 which is mounted for simple rotation about the stem 6b. This sleeve is provided with a slot 36 into which the outer end of the element 24b projects, the slot being narrower at one end than at the other and the sides of the slot being thereby inclined to the direction of movement of the slot as a whole when the sleeve 35 is rotated. The larger end of the slot 36 is sufficiently narrower than the maximum diameter of the element 24b to preclude escape of this element from the aperture 23b in the stem 6b, but when the element 24b occupies the said larger end of the slot, it is permitted to move outwardly to an extent freeing the tool element 13b as shown in Fig. 15. When the sleeve 35 is turned to bring the element 24b into the

smaller end of the slot, the inclined sides 31 of the latter act as cams to force the element 24b inwardly into the tool element retaining position as illustrated in Fig. 14. It will be apparent that in this case the element 24b operates as a stop to limit the rotational movement of the sleeve 35 in both directions.

A still further tool-retaining means is illustrated in Figs. 17 to 19 inclusive. In this case the sleeve 38, which is mounted for rotation after the manner of the sleeve 35 described above, is provided with an aperture 39 which in one position of the sleeve will register with the retaining element 24c as shown in Fig. 18. In this position of the sleeve the element 24c is permitted to move outwardly to an extent freeing the tool element 13c as previously described. When the sleeve 38 is turned, however, the inclined sides 41 of the aperture 39 act as cams to force the element 24c inwardly to an operative position as illustrated in Fig. 19 wherein the element is retained by the inner surface of the sleeve 38. In this instance the rotational movement of the sleeve is limited by an element 42 which seats in a recess 43 in the outer surface of the stem 6c and the outer end portion of which enters a slot 44 in the sleeve 38. This slot is sufficiently narrow to preclude escape of the element 42, and the manner in which it operates to limit the angular movement of the sleeve 38 will be apparent from Fig. 19 of the drawings.

The several devices for retaining the tool elements have been described in connection with one form of tool element only. It will be understood, however, that it is contemplated that other forms of tool element than that shown in Fig. 5 may be included in the device, and one such element is illustrated in Fig. 6 of the drawings. The butt end 45 of this element 47 is provided with the typical polygonal form adapting it to the socket of the stem portion of the tool holder, and this polygonal portion is also provided with notches 46 corresponding to the notches 15 of the previously described element 13. This butt formation is typical of all of the tool elements that might be included in the kit with an exception described below. The outer end of the tool element 47 is provided with a suitable socket 48 for a threading die 49.

As previously described, the outer terminal end of the stem 6 of the tool is externally hexagonal as indicated at 11. This provides for application to the end of the stem of a socket wrench element 51 as shown in Fig. 7, this element 51 having the conventional hexagonal base socket 52 which receives the hexagonal terminal portion 11 of the stem. It will be apparent that other types of tool element may be employed without departure from the invention.

It will be apparent that each of the devices described above provides an efficient, economical and readily manipulated means for positive retention of the various tool elements which may be included in the kit. It is apparent also that the device as a whole constitutes a compact and highly flexible tool having desirable characteristics of simplicity of form and manufacture combined with the ruggedness and durability required in a utility tool of the type involved.

We claim:

1. In a tool of the character described, a stem having a tool-receiving socket, an aperture in the wall of said socket having an inner end of reduced diameter, an element occupying said

aperture and of a size to project in part through the reduced inner end of the aperture, a sleeve adjustable on the stem and forming a housing for said element, said sleeve having an inner inclined wall constituting a cam operative when the sleeve is adjusted longitudinally on the stem in one direction to confine the said element to the inner end of the said aperture, and when the sleeve is adjusted in reverse direction to free the element for movement outwardly to an extent clearing the inner end of the aperture, and a resilient element also housed within the said sleeve exerts resilient pressure on the stem to create friction tending to immobilize the sleeve in adjusted position.

2. A tool in accordance with claim 1 wherein the said sleeve is provided at one end and in the inner stem-confronting surface thereof with a recess, and with a spring constituting the said resilient element, housed within said recess and tensioned to exert pressure against the stem so as to create friction tending to immobilize the sleeve on the stem.

3. In a tool of the character described, a stem having a tool receiving socket of polygonal cross section, an aperture in the wall of said socket at the juncture of two of the walls thereof, said aperture having an inner end of reduced diameter, an element occupying said aperture and of a size to project in part through the reduced inner end of the aperture, and a sleeve adjustable on the stem and forming a housing for said element, said sleeve having an inner inclined wall constituting a cam operative when the sleeve is adjusted longitudinally on the stem in one direction to confine the said element to the inner end of the said aperture, and when the sleeve is adjusted in reverse direction to free the element for movement outwardly to an extent clearing the inner end of the aperture, and a tool element having a polygonal butt to fit said socket and having at the juncture of two of the sides thereof a notch arranged so as to register with the said socket aperture when the tool element is normally seated in the socket.

4. A tool in accordance with claim 3 wherein the tool element is provided with one of said notches at the juncture of each adjoining pair of sides, said notches occupying a common plane normal to the longitudinal axis of said element and being registerable with said aperture as described.

5. In a tool of the character described, a stem having a tool receiving socket of polygonal cross section, an aperture in the wall of said socket at the juncture of two of the walls thereof, said aperture having an inner end of reduced diameter, an element occupying said aperture and of a size to project in part through the reduced inner end of the aperture, a sleeve adjustable on the stem and having an element-engaging portion inclined to the direction of the adjustment movement and constituting a cam operative when the sleeve is adjusted on the stem in one direction to confine the said element to the inner end of the said aperture, and when the sleeve is adjusted in reverse direction to free the element for movement outwardly to an extent clearing the inner end of the aperture, and a tool element having a polygonal butt to fit said socket and having at the juncture of two of the sides thereof a notch arranged so as to register with the said socket aperture when the tool element is normally seated in the socket for reception of the projecting end

6. A tool in accordance with claim 3 wherein the tool element is provided with one of said notches at the juncture of each adjoining pair of sides, said notches occupying a common plane normal to the longitudinal axis of said element and being registerable with said aperture as described.

7. In a tool of the character described, a stem having a tool-receiving socket of polygonal cross section, an aperture in the wall of said socket at the juncture of two of the walls thereof, said aperture having an inner end of reduced diameter, an element occupying said aperture and of a size to project in part through the reduced inner end of the aperture, and a sleeve threaded on the stem and adjustable longitudinally thereof by action of the threads when the sleeve is rotated, said sleeve having an element engaging portion inclined to the direction of the adjustment movement and constituting a cam operative when the sleeve is adjusted on the stem in one direction to confine the said element to the inner end of the said aperture, and when the sleeve is adjusted in reverse direction to free the element for movement outwardly to an extent clearing the inner end of the aperture.

8. In a tool of the character described, a stem having a tool-receiving socket of polygonal cross section, an aperture in the wall of said socket at the juncture of two of the walls thereof, said aperture having an inner end of reduced diameter, an element occupying said aperture and of a size to project in part through the reduced inner end of the aperture, and a sleeve mounted for rotational movement around the stem and having a slot tapered circumferentially of the sleeve and into which the said element projects for engagement with the inclined edges of the slot, said edges constituting a cam operative when the sleeve is adjusted around the stem in one direction to confine the said element to the inner end of the said aperture, and when the sleeve is adjusted in reverse direction to free the element for movement outwardly to an extent clearing the inner end of the aperture.

9. A tool according to claim 8 wherein the tapered slot of the sleeve is dimensioned to retain the said element within the sleeve while permitting the said outward movement thereof required to clear the inner end of the socket wall aperture.

10. In a tool of the character described, a stem having a tool receiving socket of polygonal cross section, an aperture in the wall of said socket at the juncture of two of the walls thereof, said aperture having an inner end of reduced diameter, an element occupying said aperture and of a size to project in part through the reduced inner end of the aperture, a sleeve having threaded engagement with the stem and adjustable by rotation through the medium of said thread longitudinally of the stem, said sleeve having a chamber housing said element and of a depth permitting outward movement of the element in the aperture to an extent clearing the inner end of the aperture, and a wall surface at an end of said chamber inclined to the axis of the stem and arranged to engage the outer end of said element when the sleeve is adjusted longitudinally to cam the element to the inner end of said aperture.
